[57] ABSTRACT

The invention is directed to work trousers which are provided with effective ventilation by inserting a gusset on the inner side of the leg pieces of the work trousers, which gusset is constructed to provide two vent channels in the gusset.

WORK TROUSERS

This invention relates to trousers. In particular, the invention is directed to work trousers made of substantially airtight material.

The problem of ventilation presents itself especially with work trousers wherein, by virtue of perspiration due to physical exertion, a permanent damp state exists. The problem of ventilation is aggravated in situations where work trousers are made of substantially airtight material in that ventilation is, practically, not possible at all. Particularly, this invention is directed to providing ventilation in the very region where the greatest amount of perspiration is secreted, viz., between the legs.

The invention is directed to providing effective ventilation without hampering or impairing the physical activity of the wearer of the work trousers and yet maintaining the protective advantage of the material employed in the work trousers. In the past, trousers have been provided with vent openings. However, these openings have been disposed either immediately below the waistline and parallel thereto or else at the front of the trousers. These slits or vent openings permitted only incomplete ventilation, for the openings were not disposed in the very region where the greatest amount of perspiration is secreted, viz., between the legs.

Use of pierced eyelets to provide openings in the leg pieces of trousers had the disadvantage of impairing the walking and movement capability of the wearer. Moreover, such eyelets provided a potential risk of damaging trousers by the rubbing action of such eyelets against the trouser material. Obviously, the risk of damaging the trousers increased when eyelets were placed on the inner leg piece of the trousers due to such rubbing action.

Slits in the seats of the trousers had the disadvantages of opening when the wearer of the trousers sat down. Thus, even if the trousers were made of water- and/or chemical-repellent material, the trousers lost their protective effect.

The instant invention is directed to providing effective ventilation without the aforementioned disadvantages. The instant invention provides effective ventilation and yet does not interfere with mobility or decrease agility, and yet provides complete protection in those instances which would require water- and/or chemical-repellent work trousers.

The instant invention is directed to a gusset to be inserted in the inner leg piece of trousers, or in crotch section of trousers, to provide ventilation. The gusset provides ventilation by virtue of construction of the gusset which has effectively two vent channels. The invention is generally directed to a pair of trousers, having an opening in the inner section of each leg piece of said trousers, and a gusset for the opening in the inner leg piece section which conforms to the shape of the opening and is attached thereto, which gusset comprises three pieces of material, two of said pieces of material overlapping with the third piece of material to form vent channels. The desirable features of this invention will become apparent on consideration of the drawings.

The drawing shows an embodiment of the invention in a partial sectional view.

In the drawings, the trousers 1, may be made of substantially air-tight material. The trousers 1 have a gus-

set 2 composed of two halves 3 and 4, each of which extend along one of the leg pieces 6 or 7. The two gusset halves 3 and 4 may stretch from the seat piece along the leg pieces 6 and 7 and may taper off towards the bottom. The gusset halves 3 and 4 comprise an outer insertion 8 and an inner insertion 9. The outer insertion 8 and the inner insertion 9 overlap each other. The overlapping of outer insertion 8 and inner insertion 9 provide the vent panels which provide ventilation, as 10 will become apparent below.

Each inner insertion 9 extends from one of the lower ends of gusset 2 to the seat piece 5, whereby the upper edges 10 are positioned so as to form an opening between them and the inside of the trousers.

15 On its upper ends, each insertion 9 is covered by the corresponding outer insertion 8. The outer insertion 8 is attached to the remaining trouser piece 13 along its two side edges 12, so that edge 14 of outer insertion 8 lies loosely against the corresponding inner insertion.

20 At least one edge 14 of outer insertions 8 should lie loosely against the corresponding inner insertions 9, so that the gusset has at least one vent channel. Thus it is apparent that the gusset of this invention may be formed of two pieces of material which overlap to form one vent channel. However, preferably for maximum ventilation, both edges 14 of outer insertions 8 lie loosely against the inner insertions 9 to form two vent channels.

25 The method of attaching outer insertion 8 to the trouser piece 13 depends on the materials employed to form the trousers and the material forming the gusset. Since edge 14 lies loosely against the corresponding inner insertion, a vent passage 15 remains open extending from the trouser's outer side to the trouser's inner side. The vent passage results from the described placement of the upper edges 10 of the inner insertion 9.

30 As indicated by the description of the drawings above, the passage 15 and the opening 10 form a vent channel, allowing the passage of air into the trousers. The passage 15 and the opening 10 allow for ventilation and evaporation of moisture, on the one hand. On the other hand, the gusset formed by the arrangement of the two gusset halves, 3 and 4, assist in retaining the protective properties, particularly desirable in water- and chemical-repellent trousers. Moreover, the invention provides for ventilation in trousers, particularly work trousers, without hindering the movements, mobility and agility of the wearer.

35 40 45 50 55 While the invention will be described below in connection with the preferred embodiment, it will be understood that it is not intended to limit the invention to that embodiment. On the contrary, it is intended to cover all alternatives, modifications, and equivalents as may be included within the spirit and the scope of the invention as defined by the appended claims.

55 60 65 70 75 80 85 90 95 Broadly stated, the invention is a gusset for trousers which provides effective ventilation, particularly between the legs. This invention finds particular utility in trousers which are made of substantially air-tight material. Such air-tight material may be selected from natural or synthetic rubbers, plastics and fabrics of natural or synthetic fibers or mixtures thereof which have been rendered water- or chemical-repellent by virtue of coating or coating procedures. The gusset which is arbitrarily comprised of two halves, 3 and 4, may be formed of the same material as the trousers or of different material. Depending on the nature of the two types

of material employed for the trousers and the gusset insert, attachment of the gusset to the trousers may be effected by sewing, by adhesives or by heat treatment. As described in the drawings, the two halves, 3 and 4, of the gusset comprise outer insertion 8 and inner insertion 9. Preferably the outer insertions 8 are two independent pieces which are attached to each other. When outer insertions 8 are independent pieces, they can be shaped to conform to the outline of the body in that area. However, it is within the scope of this invention that the two outer insertions 8 of the gusset halves, 3 and 4, consist of one piece of material. Preferably, irrespective of whether outer insertions 8 of the two gusset halves, 3 and 4, are two independent pieces or one piece, the two gusset halves, 3 and 4, stretch from the seat piece along one of the leg pieces 6 or 7 and taper off towards the bottom, as shown in the drawing.

It is apparent that there has been provided, in accordance with the invention, a modification for work trousers that fully satisfies the objects, aims, and advantages set forth above. While the invention has been described in conjunction with specific embodiments thereof, it is evident that many alternatives, modifications and variations will be apparent to those skilled in the art in light of the foregoing description. Accordingly, it is intended to embrace all such alternatives, modifications, and variations as fall within the spirit and broad scope of the appended claims.

What is claimed is:

1. Trousers provided with a gusset for ventilation, wherein said trousers comprise two leg pieces connected to each other and forming the crotch section along the inner portion of each leg piece and wherein the seat of the trousers is formed by a portion of the leg pieces connected to each other, said trousers having an opening in said crotch section formed by said leg pieces, said gusset being fitted into said opening and attached thereto along the entire periphery of said opening wherein said gusset comprises three pieces of material, one of said pieces of material being centrally positioned in said opening and having one of the other of said pieces on each side thereof, overlapping therewith

and unsecured thereto, thereby forming a concealed vent opening into the crotch area between said centrally positioned pieces of material and each of the other of said pieces of material.

5 2. Trousers, in accordance with claim 1, wherein the trousers are formed of substantially air-tight material.

3. Trousers, in accordance with claim 1, wherein the opening in the inner leg piece section tapers off on the inner side of each leg piece of said trousers.

4. Trousers, in accordance with claim 1, wherein the gusset stretches from the seat piece along the leg pieces of said trousers.

5 5. Trousers provided with a gusset for ventilation, wherein said trousers comprise two leg pieces connected to each other and forming the crotch section along the inner portion of each leg piece and wherein the seat of the trousers is formed by a portion of the leg pieces connected to each other, said trousers having an opening in said crotch section and extending downwardly along the inner side of each of said leg pieces, said gusset being fitted into said opening and attached thereto along the entire periphery of said opening, wherein said gusset is composed of two halves, wherein each one of said gusset halves extends from the crotch section down the inner side of one of said leg pieces of said trousers and tapers off downward from the seat, wherein each said gusset half comprises an outer and an inner insertion wherein the outer and inner insertions of said gusset half overlap and the edge of the outer insertion which overlaps with said inner insertion lies loosely against said inner insertion to form a concealed vent channel therebetween, said gusset halves being connected together at said crotch section.

6. Trousers, in accordance with claim 5, wherein said trousers are formed of substantially air-tight material.

7. Trousers, in accordance with claim 5, wherein the opening in the crotch section tapers off on the inner side of each leg piece of said trousers.

8. Trousers, in accordance with claim 5, wherein the gusset extends from the seat piece along the leg pieces of said trousers.
